VARIABLE PRESSURE HYDRAULIC SYSTEM
Stanley Thomas Hogg, Merrick, N.Y., assignor to American Machine & Foundry Company, a corporation of New Jersey

Filed Sept. 15, 1960, Ser. No. 56,165
1 Claim. (Cl. 60—54.5)

This invention relates in general to hydraulic systems and, more particularly, to hydraulic systems wherein the pressure may be varied over a wide range.

An object of this invention is to provide a hydraulic system which is capable of more versatile operation from a constant input pressure source.

Another object of this invention is to provide a hydraulic system having a working cylinder and a pressure intensification cylinder in which an infinite variety of pressures up to the maximum pressure produced by the pressure intensification cylinder may be applied to the working cylinder.

A further object of this invention is to provide a simple pressure intensification system which may be used in connection with a hydraulic work producing device to increase the force which may be applied by the work producing device.

A still further object of this invention is to provide a hydraulic system in which a given pressure source and a given work cylinder may be used to apply a greater working force.

Still another object of this invention is to provide a hydraulic system which is simple in its construction and which requires fewer hydraulic connections to apply a wider range of pressures to a hydraulically operated device.

Yet another object of this invention is to provide a hydraulic system to activate a work cylinder and move its piston rapidly against little or no resisting force and in which the work cylinder may be further activated by the hydraulic system to move more slowly and apply a larger force.

Additional objects, advantages and features of invention reside in the construction, arrangement and combination of parts involved in the embodiment of the invention and its practice as will be understood from the following description and accompanying drawing wherein:

The single figure of the drawing is a schematic illustration of the invention with the work cylinder and the pressure intensification cylinder shown in longitudinal cross-section.

Referring to the drawing in detail, a pipe, tube, hose or the like is designated by the reference numeral 33 and is connected to a source of hydraulic fluid under pressure. The source of hydraulic pressure may be a pump 41 which draws hydraulic fluid 37 from the sump 36 through the tube 42, or the source of hydraulic pressure may be a manifold which supplies hydraulic fluid under pressure to other devices on an existing machine. On one particular machine a manifold pressure of 250 pounds is applied to pipe 33 as this pressure operates other mechanisms and therefore cannot be varied. When the two-way valve 34 is turned so that hydraulic fluid under pressure may flow from pipe 33 into pipe 32, the pressure regulating valve or controlled pressure drop valve 30 allows hydraulic fluid to pass through it until the pressure for which the valve 30 is set builds up in pipe 27 to the pressure for which the pre-set valve 30 is set. A pipe 29 bypasses the controlled pressure drop valve 30, but the higher pressure in pipe 32 cannot flow about the controlled pressure drop valve 30 through the bypass 29 because the check valve 28 blocks it. The hydraulic fluid at the selected lower pressure which passes through the controlled pressure drop valve 30 flows through pipe 27 and through the port 40 in the smaller end 19 of the pressure intensification cylinder which is generally designated by the numeral 60.

2

The hydraulic fluid then flows through the smaller end 19 of the pressure intensification cylinder 60 and then through pipe 17 into a work cylinder generally designated by the numeral 50.

5 Disposed external to one end of the casing 14 of the work cylinder 50 there is placed a work piece holding vice having a base 10 and a jaw 11 which is fixed or secured to the base 10. A movable jaw 12 is slidably secured to the base 10 and is moved toward the stationary jaw 11 by a piston rod 13 which is attached to it. Within the work cylinder casing 14 there is disposed a piston 15 which acts on the piston rod 13 to urge jaw 12 towards the fixed jaw 11. Therefore, as shown in the drawing, when pressure from a hydraulic pressure source flows through pipe 33 and past valve 30 with a controlled pressure into the work cylinder 50, the hydraulic fluid at a selected pressure will urge the piston 15 to the right so that the work pieces 20 will be held between the jaws 11 and 12. If the source of hydraulic pressure which is connected to pipe 33, such as pump 41, can only deliver a given number of cubic inches of hydraulic fluid per second at a given pressure, a relatively small diameter work cylinder 50 will more rapidly move jaw 12 towards jaw 11 to grip the work pieces 20.

When the work pieces 20 are clamped between the jaws 25 11 and 12 as shown in the drawing, the force exerted on the work pieces 20 by the jaws 11 and 12 will be determined by the area of the piston face of piston 15 and the pressure which the pressure regulating valve 30 is set to pass. By varying the setting of valve 30 from zero to the 30 pressure available from the hydraulic pressure source, a range of forces may be applied to jaw 12 by the work cylinder 50.

When it is desired to apply greater force on work pieces 20 by jaw 12, the line valve 26 is opened allowing hydraulic fluid to flow behind piston 22 within the large portion 18 of the pressure intensification cylinder 60. The larger area of the piston face of piston 22 compared to the piston face of the pressure intensification piston 23 causes the pistons 22 and 23 to move to the left as shown in the drawing. As piston 23 moves to the left, it passes the port 40 and effectively closes it so that hydraulic fluid cannot flow from the smaller portion 19 of the pressure intensification cylinder 60 back down pipe 27. As additional hydraulic fluid at a controlled pressure flows past valve 30 and valve 26 through pipe 25 into the pressure intensification cylinder 60, the pressure in the smaller portion 19 of the pressure intensification cylinder becomes a multiple of the pressure passed by pressure regulating valve 30 and exerted on the larger piston 22. The multiple by which 45 the pressure intensification cylinder increases the pressure is determined by the ratio of the areas of the piston faces of piston 22 and the pressure intensification piston 23. As the pressure intensification piston 23 moves further to the left as shown in the drawing, hydraulic fluid under this 50 intensified pressure flows through pipe 17 to exert a correspondingly increased pressure on piston 15. The increased pressure on piston 15 increases the force exerted on the movable jaw 12 which then more tightly clamps the work pieces 20.

60 After a desired operation is performed on the work pieces 20 while they are clamped between the jaws 11 and 12, the two-way valve 34 is turned so that pipe 32 is connected to drain pipe 35 which leads to the sump 36 which catches hydraulic fluid 37 draining from the system. 65 When pipe 32 is connected to drain 35, pressure in pipe 32 falls to zero. Within the work cylinder 50 a compression spring 16 is constantly urging piston 15 to the left. In a like manner, a spring 24 in the pressure intensification cylinder 60 is constantly urging the pistons 22 and 23 to the right. The spring 24 urges piston 22 to the right forcing fluid within the large portion 18 of pressure intensification cylinder 60 to flow out through pipe 25

and then through the opened valve 26. As soon as piston 23 uncovers port 40, spring 16 may urge piston 15 to the left to force hydraulic fluid through pipe 17 and pipes 27. The fluid which is forced from the work cylinder 50 and the pressure intensification cylinder 60 by the springs 16 and 24 flows through check valve 28 into the sump 36 where it may be withdrawn by pump 41 or any other suitable hydraulic pressure source.

When it is again desired to activate work cylinder 50 and close jaws 11 and 12, valve 34 is again set to connect pipes 33 and 32 whereupon the cycle may be repeated. It is to be noted that if the valve 26 is left closed, the regulating valve 30 may be used to directly control the hydraulic pressure within the work cylinder 50 and the force exerted by jaw 12 on the work pieces 20.

If an existing machine has a work cylinder or other hydraulic device activated from a source of hydraulic fluid under pressure through a controlled pressure drop valve to vary the force exerted by the work cylinder, a relatively simple modification of an existing machine according to this invention may increase the force exerted by the work cylinder by any desired multiple. For example, in certain cut-off machines on the market having a work-holding fixture actuated by hydraulic pressure, supplied from a hydraulic source through a manifold, the pressure in the hydraulic manifold is of a constant value which cannot conveniently be changed for the reason that such machines have various other elements activated from the manifold. This invention is readily adapted to such machines where it is desired to have a wider range of clamping force on the work-holding fixture.

Thus the invention may be readily adapted to existing machines as well as being easily built into new machines. If this invention is applied to an existing machine, the machine's hydraulic system need not be affected as the machine may be conventionally operated without activating the pressure intensification cylinder.

The arrangement of the valve 30 with the pressure intensification cylinder 60 permits an infinite selection of pressure values to the work piston 15 from zero to a value equal to the product of the value of the pressure source by the pressure intensification cylinder multiple. Pressures less than the pressure source may be obtained by closing the valve 26 so that the pressure intensification cylinder is bypassed. Pressures above the source pressure may be obtained by opening the valve 26 and suitably adjusting the valve 30.

The spring 24 should be set to counter-balance piston 22 to resist a hydraulic force greater than the hydraulic force on piston 15 resisted by spring 16. This assures that the port 40 will not be closed until the jaw 12 has contacted the workpiece.

Although a work piece holding device is shown being activated by the work cylinder 50, this invention may be used for many other purposes.

While I have disclosed my invention in the best form known to me, it is to be understood that this is purely

exemplary and that modifications in the construction, arrangement and combination of parts and the substitution of equivalents mechanically and otherwise may be made without departing from the spirit of the invention except as it may be limited in the appended claim.

I claim:

In a hydraulic system, a reservoir for hydraulic fluid, said reservoir connected through a source of hydraulic fluid under pressure, a controlled pressure drop mechanism in a line from the source of hydraulic fluid under pressure, a two way valve which in a first position connects the controlled pressure drop mechanism to the source of hydraulic fluid under pressure and in a second position communicates the controlled pressure drop mechanism with the reservoir, a check valve connected across the controlled pressure drop mechanism to permit flow only from the outlet of the controlled pressure drop mechanism to the inlet thereof, said two way valve thus being operable to selectively direct fluid from said source of hydraulic fluid under pressure toward said controlled pressure drop valve and from said check valve to said reservoir, a pressure intensification cylinder having a larger portion and a smaller portion, a piston having a larger portion and a smaller portion reciprocable in said larger portion and said smaller portion of said cylinder, respectively, the smaller portion of the cylinder having a side port, a spring in the pressure intensification cylinder biasing the piston to its retracted position, a first conduit communicating the pressure drop mechanism to the side port, said port being in communication with the working chamber of the intensification cylinder when the piston is in the retracted position, and a second conduit communication the pressure drop mechanism to the larger portion of the pressure intensification cylinder, a valve in said second conduit, a hydraulic motor having a piston therein, said motor communicating with the smaller portion of said pressure intensification cylinder, and means normally biasing the piston in said hydraulic motor to its inactive position.
